(57) **CLAIM**

The ornamental design for a support chair for poured concrete reinforcement members, as shown and described.

DESCRIPTION

FIG. 1 is a perspective view, taken from the top, front, and side, of a support chair for poured concrete reinforcement members, in accordance with our new design.

FIG. 2 is a front elevation view of the support chair for poured concrete reinforcement members shown in FIG. 1.

FIG. 3 is a rear elevation view of the support chair for poured concrete reinforcement members shown in FIG. 1.

FIG. 4 is a right side elevation view of the support chair for poured concrete reinforcement members shown in FIG. 1.

FIG. 5 is a left side elevation view of the support chair for poured concrete reinforcement members shown in FIG. 1.

FIG. 6 is top plan view of the support chair for poured concrete reinforcement members shown in FIG. 1; and,

FIG. 7 is a bottom plan view of the support chair for poured concrete reinforcement members shown in FIG. 1.

The broken lines illustrate environmental structure which forms no part of the claimed design.

1 Claim, 7 Drawing Sheets
